DEVICE FOR APPLYING A WRAPPER TO A BUNCH OF CIGARILLOS OR CIGARS

Everardus W. C. van Buul, Eindhoven, Netherlands, assignor to N. V. Vereenigde Tabaksindustrieën Mignot & De Block, Eindhoven, Netherlands

Application January 21, 1950, Serial No. 139,851
In the Netherlands January 24, 1949

2 Claims. (Cl. 131—37)

1

The invention relates to a device for applying a wrapper to the bunch of a cigarillo or a cigar by means of a rolling mechanism comprising a set of rollers, into which the wrapper is manually fed.

If the wrapper is fed by hand into the rolling mechanism the cigarmaker applies an adhesive paste to the rear end or the flag of said wrapper with his fingers. In that case the rear end or the flag, if any, of the wrapper meant for covering the head of the cigarillo or the cigar to be made, is drawn across a finger provided with paste. This method has several disadvantages namely, the cigarmaker must be skilled, he gets sticky fingers and he cannot prevent that other parts of the wrapper than the flag are smeared with paste. Moreover the rolling mechanism has to be stopped momentarily in order to enable the cigarmaker to apply paste to the flag of the wrapper.

The invention has for its object to provide means overcoming these disadvantages and conducive to a device, which makes it unnecessary to stop the rolling mechanism for the purpose of applying paste to the flag or the rear end of the wrapper. Thus, the production of the rolling mechanism can be considerably increased. The invention contemplates that in front of the location, where the wrapper is fed through the gap between two rollers of the rolling mechanism, a guiding member, for example a plate or a roller, is provided extending through a part of the length of said rollers at the end, where the head of the cigarillo or the cigar is made. It is still another object of the invention to provide means for periodically applying paste to said guiding member.

In this device the cigarmaker need only to press the flag or the rear end of the wrapper with his finger on said guiding member in order to have the lower side of said flag or rear end pasted. Owing to the rotation of the rollers of the rolling mechanism the wrapper is drawn automatically into the space surrounded by said rollers and the flag or rear end of the wrapper is slid across the guiding plate or the guiding roller in contact therewith. It has been found that for making the head of the cigarillo or the cigar the rolling mechanism need not to be stopped, so that an increase of production of 10-20% can easily be obtained.

In order to avoid that the cigarmaker is hampered, when applying the flag or the rear end of the wrapper to the head of the bunch, by the paste applying parts, the guiding member may be advantageously so constructed that it is adapt-

2

ed to move from and towards the rolling mechanism. The means for applying paste to said guiding member may become active when said guiding member is removed from the rolling mechanism, so that they may be provided at a place where they do not hamper the cigarmaker when controlling the movement of the rear or flag end of the wrapper during the feeding thereof to the rolling mechanism.

10 For detailed explanation of the invention reference is made to the accompanying drawings, in which:

Fig. 1 is a perspective view of a device made according to the invention having a guiding member or plate for applying paste to the flag or rear end of a cigar or like wrapper.

Fig. 2 is a part of a similar device, in which for the guiding member, is in form of a roller.

Fig. 3 is a sectional view of the device of Fig. 2 seen in one end position.

Fig. 4 is a sectional view of the device of Fig. 1 seen in another end position.

Fig. 5 is a front elevational view of the device of Fig. 4.

25 In the drawings there are seen and designated by numerals 1, 2, 3 and 4 four rollers of a known rolling mechanism by means of which a binder leaf can be wound around a portion of scrap tobacco and a wrapper leaf can be wound around the bunch thus obtained. The binder leaf and the wrapper leaf are introduced into the rolling mechanism through a gap provided between the rollers 1 and 2 and are seized by the scrap tobacco or the bunch, respectively, which is contained in the space defined and surrounded by said rollers 1, 2, 3 and 4. Near the forward end of the mechanism constituted by conical ends 5, 6, 7, 8, 9, 10 of the rollers, which ends are formed by solid cones or conically wound helical springs, a guiding plate or member 11 is provided which in one position is in front of the gap between the rollers 1 and 2 (Fig. 3). In that position said guiding plate 11 extends a relatively small distance from and near the end of the rolling mechanism, where the head of the cigarillo or the cigar is formed. It partly covers roller 1 and its conical end 5. If the wrapper is drawn into the rolling mechanism it is slid with its rear end or flag across the guiding plate 11 in contact therewith.

40 This plate 11 is supported by an arm 12, which is secured to a rotatably mounted shaft 13 carrying also arms 14 and 15. The arm or extension 14 abuts against the arm 16 of a two-armed lever, which is rotatably mounted about a horizontal shaft 17 journalled in a suitable bearing 17a.

45 55 The other arm 18 of said lever is provided with a

resilient wire applicator 19, which may be drawn into a container 21 containing an adhesive paste, by a spring 20 extending to and anchored on arm 18, said spring acting on the lever 16, 18. Attached to the arm 15 is a driving-rod 22 driven by the motor (not shown) of the cigar-making machine. If the rod 22 is pulled to the left (according to the arrow), the guiding plate 11 is moved in a direction away from the rolling mechanism and the lever 16, 18 lifts the applicator 19 out of the paste container 21 (Figs. 4 and 5).

The applicator 19 is made of thin wire metal and it is very flexible. When it is lifted (from its position 19'), it droops a little, so that the guiding plate 11 moving at the same time in a horizontal plane, is touched by said applicator. The latter slides then on the upper surface of said plate and thereby transfers a portion of the paste on said plate.

If the guiding plate is in a position (Figs. 4 and 5) remote from the rolling mechanism a binder leaf can be easily introduced in said mechanism. If, on the other hand, the rod 22 is pushed to the right (according to the arrow), the guiding plate 11 returns to its position (Fig. 3) in front of the end portion of the rolling mechanism and the wire applicator 19 is again immersed in the tank 21 containing said paste. In that position of the guiding plate 11 a wrapper (not shown) can be fed into the rolling mechanism. If the wrapper is drawn into the rolling mechanism to such an extent that the rear end or the flag thereof has reached a position vertically above the guiding plate 11, the cigarmaker need only to press said end of the wrapper on the plate by means of one of his fingers in order to have applied the paste carried by said plate to the lower side of the rear end or the flag of the wrapper. During the pasting operation the rolling mechanism need not to be stopped.

In the embodiment according to Fig. 2 the plate 11 includes a guiding roller 23. But for the inclusion of this roller the device is of the same construction as that according to Fig. 1 and operates in the same way.

Having thus described the invention, what is claimed as new and desired to be secured by Letters Patent is:

1. A device for applying a wrapper to the bunch of a cigarillo and like product; comprising, in combination, a set of rollers constituting a rolling mechanism having a forward end and into which said wrapper is to be fed, a member for receiving the flag of the wrapper, an arm adapted

to be swung about a vertical axis and carrying at its free end said member, a trough for containing adhesive paste, said trough being situated beyond said forward end of the rolling mechanism, where said head of the cigarillo is made, a reciprocably movable applicator for periodically taking paste out of said trough and applying it to said member, and driving means adapted to cause reciprocation of said arm and said member between a position at the forward end of the rollers, where the head of the cigarillo or cigar is made, and a position above the trough and in the path of the paste applying applicator, said driving means being also arranged to operatively coat with said paste applying applicator.

2. A device for adhesively applying a wrapper to the bunch of a cigarillo and like tobacco product; comprising a set of rollers including a forward end and constituting a rolling mechanism for the cigarillo to which said wrapper is to be applied, a guiding member past which the flag of said wrapper is fed to said rolling mechanism, an arm arranged for swinging movement about a vertical axis and operatively coating with said guiding member, a reservoir for containing an adhesive, said reservoir being positioned adjacent said forward end of said rolling mechanism, an applicator arranged for swinging movement about a horizontal axis and adapted to dip into said reservoir and to transfer adhesive therefrom to said guiding member, and means reciprocably moving said applicator about said horizontal axis and said guiding member about said vertical axis in timed relation to each other so that said applicator is swung out of said reservoir for transfer of adhesive to said guiding member when the latter is moved from a position adjacent said forward end of said rolling mechanism to a position above said reservoir for cooperation with said applicator.
